GARMENT HANGER

Edward H. Biuns, Pittsburgh, Pa.

Application June 12, 1936, Serial No. 84,866

5 Claims. (Cl. 223—98)

This invention is an improvement in a combined garment support and a relatively adjustable protector cooperable therewith.

The present application is a division of the 5 subject matter of my prior application Ser. No. 71,617.

The objects in view are to provide a supporting hanger provided with an elongated stem on which the protector may be mounted for vertical adjustment, the hanger yoke being preferably separably connected with the stem and protector for removal or replacement with the supported garment.

In the drawings showing certain preferred embodiments of the invention:

Fig. 1 is a view of the assembled hanger and protector in front elevation, partly in section;

Fig. 2 is a vertical sectional view on the line II—II of Fig. 1 showing the preferred stem and hanger yoke connections;

Fig. 3 is a partial view in elevation like Fig. 1 but showing a modified construction;

Fig. 4 is a similar view showing the protector elevated and suspended, utilizing a modified arrangement of the lifting mechanism.

The hanger in its entirety comprises the conventional yoke 2 of any suitable construction, over which the garment or garments 3, as a coat, cloak, dress, suit, etc. is or are draped for normal support, in the usual manner.

The yoke 2 is provided at its upper middle portion with a central vertical opening or socket 13, entirely or only partly through it, upwardly from the lower side.

Socket 13 is adapted to be engaged by a cooperating open hook 5 at the lower terminal of the elongated stem or shank 6, of wire or the like, as in Figs. 1 and 2.

At its upper end stem 6 terminates in a supporting hook 7 adapted to engage a carrying bar or rod 8. Hook 7 is extended around in the form of an engaging loop terminating in a rounded reversed eye 9 or the like, for grasping. The inner portion of the wire forming the eye 9 is rounded as shown, leaving a space 10 slightly less in width than the diameter of bar or rod 8, to prevent accidental removal therefrom. The hook 7 being somewhat resilient, allows for placement over the bar as in the usual open hook form, but with outward and reverse automatic spring action.

By withdrawing the terminal 9 of either the rounded or any other suitable form, the entire stem, with or without the yoke 2, may be easily 55 removed from the bar.

The protector 11 is in the form of an inverted open bottom bag or pouch of comparatively shallow depth, but sufficiently ample in dimensions laterally to cover the upper shoulder portions of garment 3 when lowered thereon, as in Fig. 1.

As shown, the upturned hook 5 is preferably of less length than the socket 13 and in any event should not project above it. In this manner it avoids the possibility of interference or tearing of the fabric, especially of dresses, wraps, 10 etc.

By such construction the hanger may be lowered vertically over the hook 5 for firm support of its load of garments as in Figs. 1 and 2, and as easily removed by merely elevating it vertically for clearance. The lower end portion of socket 13 is preferably flared as in Fig. 2, facilitating entrance of hook 5. Such manipulation avoids the necessity of any tilting or movement other than vertical, and renders placement and removal extremely easy and convenient.

In such case also, the retaining function of hook 7 by its resilient inwardly extending terminal is of advantage in providing for easy springing application over the bar 8 and preventing 25 accidental removal of the stem by any material degree of upward movement, incident to upward movement of the stem or lifting of the protector on the stem.

A further advantage provided by the upper 30 hook construction is illustrated in Figs. 1 and 2.

In case the protector is freely or non-frictionally mounted on the stem, merely by a small clearance opening 17 for the stem, it may be raised or lowered by a pull cord 14 attached in 35 any suitable manner to the protector, as at 15 and passed upwardly through the eye 9 and provided with a depending pulling terminal 16.

In such arrangement the protector may be elevated and held temporarily by the hand or any 40 suitable connection for the cord, and again lowered to normal position. When thus elevated and held, it leaves the operator free to use both hands in removing the garments from or replacing them on the hanger, or in removing the hanger itself 45 and its load entirely from the stem terminal, or in replacing it thereon.

I show in Fig. 3 a further modification utilizing the same general combination of elements, but in which the stem 6 is twisted on itself to 50 provide a looped eye 9a. Such loop is made in the shank of the stem, preferably closely below the hook 7, through which the cord 14 is passed in the manner above described.

The eye 9a thus provides a rounded bearing 55

for the cord, closely adjacent the stem, ensuring stability and substantially vertical disposition of the supporting cord.

5 In place of the terminal 16, the free end of the cord is provided with a counterweight 16a, properly proportioned as to weight and design as to counterbalance the protector, and to hold it suspended at any desired elevated, lowered, or intermediate position.

10 In Fig. 4 the same construction is shown except that in this case the cord 14 is provided with a terminal cross bar 16b.

The terminal cross bar may be inserted endwise through loop 9a and will then prevent complete withdrawal unless properly manipulated, thus avoiding undesired disconnection.

15 With such form, or either of the others, the cord may be looped around eye 9 as shown sufficiently to provide a holding connection, thus 20 ensuring elevated support of the protector 11 until it is desired to lower it. The cord may be then unwound and will resume its normal free sliding relation.

25 The advantage and usefulness of the invention will be easily understood and appreciated by all those familiar with the use of coat hangers, especially in connection with the merchandising of clothing, or its storage. It is especially useful where a series of hangers are suspended side by 30 side in a limited space.

The upper hook terminal provides for easy placement or removal and avoids undesired disconnection. The hook and eye connection, or the vertical hook and socket connection, between 35 the lower end of the elongated stem 6 and hanger 2 facilitates connection and disconnection in the manner stated. The elongated stem allows for vertical movement and arresting support of the protector, and the entire assemblage of these 40 elements provides a compact and very effective convenient means for the purpose intended.

45 The protector itself may be made of any suitable flexible material, conveniently shaped and in appropriate sizes, and forms a practically complete protection for the upper portions of suspended garments. I prefer to utilize in its manufacture any well known commercially available material, having the advantages of transparency, lightness, strength and pliability.

The design, shape, proportions, size, or material of the protector and its associated elements may be varied to suit varying conditions of use, and it will be understood that the invention is not limited to the exact construction disclosed. 5

What I claim is:

1. In combination with a garment hanger yoke and an elongated stem having separable connection with the yoke and an upper terminal hook provided with an endmost eye, a garment protector slidably mounted on the stem, and means for raising and lowering it thereon connected with the protector and engaging said eye. 10

2. In combination with a garment hanger and an elongated supporting stem having at its upper end a rod engaging hook provided with a looped eye, a garment protector slidably mounted on the stem, and a raising and lowering cord connected with the protector and passing through said eye. 15

3. In combination with a garment hanger and an elongated supporting stem having at its upper portion a rod engaging hook and a looped eye, a garment protector slidably mounted on the stem, and a raising and lowering cord connected with the protector and passing through the eye. 20

4. In combination with a garment hanger and an elongated stem having at its upper portion a rod engaging hook terminating in a rounded end and a lower looped bearing in the stem, a garment protector slidably mounted on the stem, and a raising and lowering cord connected with the protector passing through the looped bearing and wound about the rounded end of the hook for temporary holding suspension of the protector when raised. 30

5. In combination with a garment hanger yoke and an elongated stem having separable connection with the yoke and an upper terminal hook provided with an inwardly disposed resilient rounded end retaining portion facilitating opening placement over a supporting bar and having a looped eye, a garment protector slidably mounted on the stem, and a cord connected with the protector and engaging the eye for raising and 45 lowering the protector on the stem. 35

EDWARD H. BINNS.
